Atty's.

UNITED STATES PATENT OFFICE

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA

NEEDLE BAR FOR FULL FASHIONED KNITTING MACHINES

Application filed January 16, 1930. Serial No. 421,174.

My present invention relates to improvements in needle bars for full fashioned knitting machines.

An object of the invention is the provision of a needle bar construction having improved strength and a simple, rugged, structure.

Another object is to provide a needle bar having a needle heel receiving and supporting opening which will accurately determine the position of the needles.

A further object is the provision of a simple and efficient method of manufacture of said needle bar.

15 Other objects will appear hereinafter.

The invention consists in the features, combination, and arrangement of parts hereinafter described and particularly pointed out in the claims.

20 Referring to the drawings:

Fig. 1 is an end view of the needle bar.

Fig. 2 is a front elevation of the needle bar with the clamping plates removed and the bolts shown in section.

25 Fig. 3 is a front view of the needle bar on a reduced scale showing the clamping plates in place.

Fig. 4 is a view of the needle bar of Fig. 1 as it is when removed from the mold and 30 before it is finished and slotted.

In the drawings, 1 represents the body of the needle bar through which bolts 2 pass at intervals to threadedly connect with 35 clamping plates 3 arranged side by side along the bar.

The needle bar 1 is provided with a vertically grooved needle spacing portion or bar 4 at its upper end. The vertical grooves for 40 spacing the needles are indicated at 4a.

Beneath the needle spacing member 4 and in the vertical face of the body 1 is provided a longitudinal groove 5 for receiving the heels of the needles 6. The uniform groove 45 5 contributes to accuracy in that it is readily and accurately formed, as compared to the separate pin holes heretofore formed in needle bars for receiving the individual needle heels. The separately formed holes 50 were difficult to make with accuracy as they

were apt to be bored at an angle or on a slant or slightly out of position.

Heretofore it has been the practice to secure the needle spacing member 4 to the needle bar body 1 by first finishing the contacting surface of the needle bar body and also finishing the contacting surface of the spacing member and then fastening the two together by screws.

According to the present invention the 60 needle spacing bar 4 with its dove-tail projection 7 is placed in the needle bar molding flask in proper position and the needle bar body 1 is cast around it in the flask.

The molding process requires no finishing 65 of contacting surfaces and a more strong and massive united product results than by the screw connected finished surfaces in needle bars heretofore made.

Preferably the needle bar body 1 is cast 70 of aluminum while the needle spacing member 4 is preferably of brass. The clamping plate may be of drawn steel and is preferably provided with a facing 8 of pasteboard.

The needle spacing member is simply a 75 drawn shape, preferably of brass, cut off to length requiring no machining before the casting in the mold.

In Fig. 4 is shown the casting as it appears when removed from the mold in unfinished 80 condition with the aluminum of the needle bar body cast around the brass needle spacing member. The casting of Fig. 4 is then machined and finished and provided with the vertical grooves or slots 4a in the needle spacing member, the body member 1 being cut back beneath the member 4 and provided with the longitudinal groove 5.

The needle spacing member 4, if desired, 90 may be extended downwardly so that the longitudinal groove 5 may be cut in it instead of in the body 1.

I do not desire to limit my invention to the specific materials mentioned nor to the exact construction shown as it will be apparent that modifications may be made without departing from the scope of the invention as set forth in the claims.

I claim:

1. A needle bar for full fashioned knitting 10

machines including a body of aluminum having a needle spacing bar of brass interlockingly molded thereto, said body having a longitudinally extending groove beneath 5 said needle spacing bar for receiving the heels of the needles.

2. A needle bar for full fashioned knitting machines having a needle spacing bar molded thereto, said spacing bar being vertically 10 grooved to receive the needles, the said bar having a longitudinal groove in its vertical face to receive the heels of the needles, bolts 15 passing through the needle bar, and a series of adjoining clamping plates connected with said bolts for clamping against said needle spacing bar and needle bar.

3. A needle bar for full fashioned knitting machines comprising a member to space the needles molded with the body of the bar to 20 present a double face including an upper portion of one metal and a lower portion of a different metal, said double face having vertical needle spacing grooves therein and a longitudinal groove beneath said vertical 25 grooves to receive the heels of the needles.

4. A needle bar for full fashioned knitting machines having a vertical face provided with a series of vertical needle spacing grooves and a longitudinal groove beneath the 30 vertical groove to receive the heels of the needles, said face comprising an upper portion of brass and a lower portion of aluminum, said metals being molded together and having intimate contact throughout their contiguous surfaces.

In testimony whereof, I affix my signature.
KENNETH HOWIE.
